SHOWER-BATH DISTRIBUTOR VALVE

Jacques-Albert Deport, Paris, France

Application March 20, 1956, Serial No. 572,756

Claims priority, application France March 22, 1955

1 Claim. (Cl. 299—84)

The present invention has for its object a distributor device which is applicable to shower-bath installations of the kind referred to in Patent No. 2,672,366.

The distributor in accordance with the invention comprises a valve interposed on each of the pipes which supply respectively emulsion and clean water, and is characterised in that these valves are actuated by a rotary cam rigidly fixed to a hand-lever within the reach of the user. A further feature consists in that the profile of the cam is such that the hand lever can be left for as long a time as desired in the "shower" position, that is to say "supply of clear water," whilst if this hand lever is brought into the emulsion" position, it is automatically brought back to the "stop" position as soon as it is released, in order to avoid excessive consumption of the soap solution.

A distributor device for shower-baths, improved in this manner, is shown by way of example in the accompanying drawings in which:

Fig. 1 is a view in longitudinal cross-section taken along the line I—I of Fig. 3.

Fig. 2 is the corresponding view in plan.

Fig. 3 is a view in cross-section taken along the line III—III of Fig. 1.

Fig. 4 is a diagrammatic illustration of the development of the control cam.

The distributor device comprises a chamber 1 for the admission of the water, two outgoing pipes 2 and 3 leading to the shower-rose, a pipe 4 leading into the pipe 3 for the admission of soap solution.

The admission of each of the conduits 2 and 3 is controlled respectively by the valves 5 and 6 which are held applied against their seatings by means of the springs 7 and 8; the valve 5 controls the admission of pure water to the pipe 2 and the valve 6 the admission of water in which there has been emulsified the soap composition solution which is admitted from an ejector into the pipe 4 and is carried away by the flow of water in the pipe 3, in which pipe the ejector effect is obtained by the difference in internal diameter between the said pipe 3 and the nozzle 3a.

This ejector effect is important since it makes it possible to place the soap composition reservoir at any desired level, even below the level of the distributor valve.

The actuation of these valves is carried out by means of a cam 9 keyed on the shaft 10 of a hand lever 11 which is brought by the user, by rotation, opposite one of the indications "Shower," "Stop," "Lather" marked on a dial 12. The cam 9 has two sloping faces 13 and 14 which act respectively on the spindles 15 and 16 of the valves 5 and 6, against the action of the springs 7 and 8. As shown in Fig. 4, the profile of the working surface 13 is such that in the "Shower" position, the spindle 15 of the valve 5 passes over this surface and comes at 15a into contact with a flat face of the cam,

2

in such manner that the position of the lever handle is stable and thus the clear water can continue to flow as long as the user does not bring back the hand lever to the "Stop" position; on the other hand, in the "Lather" position, the spindle 16 of the valve 6 remains in contact at the position 16a with the sloping face 14 and, if the hand lever is then released, the pressure applied by the spindle 16 of the valve 6 will cause the hand lever to rotate towards the "Stop" position. This arrangement prevents waste of the soap composition by ensuring that its supply is automatically shut-off as soon as the user releases the hand lever.

A safety valve 17 controlled by a spring 18, is preferably mounted inside the pipe 4; this valve is provided with the object of preventing back-flow of the water delivered by the pipe 2, through the pipe 3 towards the reservoir of soap composition, in the case in which the flow of water is restricted for any particular reason (furring or blocking of the pipes, etc.).

20 The invention is also held to cover the possibility of controlling the safety valve 17 by the actual operation of the lever handle 11 of the distributor valve, the said safety valve being normally closed and only being opened by the effect of the action of admitting water to the pipe 3.

What I claim is:

A shower-bath apparatus, comprising: a distributor valve having a water admission chamber connectible to a water supply pipe, and two distribution channels, one 30 of said channels at its inner end having a portion of narrow cross-sectional area, followed by a flared, frusto-conical portion; an admission pipe for delivering soap into said frusto-conical portion; a check valve in said admission pipe for preventing flow of liquids outwardly 35 therethrough; a pair of valves, each valve having an actuating stem, one valve controlling communication between said chamber, and said one channel, the other valve controlling communication between said chamber and the other channel; a rotatable actuating lever movable into two terminal positions and an intermediate position; a cam disc having a face bearing against said valve stems for actuation thereof, said face having a raised planar portion perpendicular to the axis of rotation thereof for bearing against the stem of said other valve, said face also having a portion sloping away therefrom for bearing against the stem of said one valve, 45 said cam disc in the intermediate position of said actuating lever having its face bearing against said stems and permitting both of said valves to close, said cam disc in one terminal position of said actuating lever having its raised planar portion engaging the stem of said other valve, whereby said other valve is opened to permit flow of water through said other channel, said cam disc in the other terminal position of said actuating lever 50 having its sloping portion engaging the stem of said one valve, whereby said one valve is opened to admit water to said one channel, whereby soap is aspirated into said one channel and is mixed with water, said one valve being in an unstable condition when open so that it is 55 automatically urged to return to a closed condition, and said other valve being in a stable condition when open.
